UNITED STATES PATENT OFFICE

2,484,492

SEGMENTAL BOX-TYPE WRENCH WITH
PIVOTED LEVERS

John C. Dingley, Rexburg, Idaho, assignor of one-half to Sheldon J. Morris, Pacoima, Calif.

Application August 12, 1946, Serial No. 690,005

2 Claims. (Cl. 81—121)

1

The invention relates to a hand tool, and more especially to a work enclosing wrench.

The primary object of the invention is the provision of a wrench of this character, wherein it is of the closed-end type, so that nuts located on tubes, pipes, rods or the like, as used on fuel lines, conduits, etc., which are inaccessible to box type wrenches, can be manipulated with ease and dispatch, the wrench being once fitted on a nut in an obscure and unhandy place, will not slip off in case the user's hand slips off of the said wrench.

Another object of the invention is the provision of a wrench of this character, wherein it is novel in construction, unique in the set-up of the same, it being handy for close work service, and is latched when engaged about the work, without possibility of slipping from place, and is convenient for operation thereof.

A further object of the invention is the provision of a wrench of this character, wherein it is adaptable for engaging a piece of work from either end thereof, as there are companion jaws at opposite ends of the same, these being of the closing-in type, and are latched together when in engaging position.

A still further object of the invention is the provision of a wrench of this character, which is simple in construction, thoroughly reliable and efficient in operation, readily and easily applied and removed to and from the work, strong, durable, possessed of few parts, and inexpensive to manufacture and install.

With these and other objects in view the invention consists in the features of construction, combination and arrangement of parts as will be hereinafter more fully described, illustrated in the accompanying drawing, which discloses the preferred embodiment of the invention, and pointed out in the claims hereunto appended.

In the accompanying drawing:

Figure 1 is a plan view of the wrench constructed in accordance with the invention and in a work engaged position.

Figure 2 is an end elevation.

Figure 3 is a perspective view showing the wrench opened.

Figure 4 is a fragmentary perspective view showing a portion of a rod having a nut formation, with the wrench about to be engaged with the latter.

Figure 5 is a fragmentary plan view of one closing-in end of the wrench.

Figure 6 is an end elevation thereof.

Similar reference characters indicate corre-

2

sponding parts throughout the several views in the drawing.

Referring to the drawing in detail, the wrench constituting the present invention, denoted generally at A, comprises a pair of crossed levers 10, each having the reversely curved outer portions 11, pairs of the latter matching each other adjacent to one another when the levers 10 are brought in parallel relation, one to the other.

10 On the end portions 11 of the levers 10 are oppositely disposed outwardly arched substantially half circular shaped work engaging jaws 12, the levers 10 being swingingly connected together side-by-side intermediate of their portions 15 11 by a pivot in the form of a detachable fastener 13, so that such levers have an action for the engagement of the jaws 12 and the disengagement of the same, to and from a nut, the hex-type thereof being generally denoted at B, in this 20 instance formed on a rod, as identified at C, best seen in Figure 4 of the drawing.

The opposed jaws 12 at their inner surfaces are corrugated as at 14, so that these jaws when closed-in on a nut will firmly grip the same to 25 prevent relative slipping movements therebetween. The opposite jaws 12 at their outermost terminal portions are provided with interlocking keepers 15 which function as latches for holding the said opposite jaws fastened together 30 when embracing a piece of work, as for example a nut B, and thereby maintaining a positive engagement, in case the user's hand slips off the wrench.

This type wrench is designed to facilitate use of a closed-end wrench on a hex unit nut located 35 on a pipe, tube, fuel line, conduit, etc., which is inaccessible to box wrenches, and involves all advantages of the closed end wrenches.

The jaws 12 when approaching each other at opposite ends of the levers become automatically 40 latched together, as should be obvious from Figures 1 and 5 of the drawing, and also as at Figures 2 and 6 thereof.

The portions 11 reversely off-set the jaws in 45 their pairs at opposite ends of the wrench A, as will be apparent from the drawings, which enables convenient leverage thereto.

What is claimed is:

1. A wrench of the kind described, comprising a pair of elongated levers arranged side-by-side for matched relation to each other, a pivot connecting the levers intermediate of their length for side-by-side swinging movement in and out of matched relation to each other, and laterally projected socket forming jaw portions on the levers which will match to encircle a piece of work

when the levers are brought to a matched relation to each other.

2. A wrench of the kind described, comprising a pair of levers arranged side-by-side for matched relation to each other, a pivot connecting the levers intermediate of their length for side-by-side swinging movement in and out of matched relation to each other, a laterally projected socket forming portion on each lever which will match to encircle a piece of work when the levers are brought to a matched relation to each other, and means interlocking the jaw portions when the levers are in matched relation for preventing lateral spreading thereof.

JOHN C. DINGLEY.
